his Attorney

UNITED STATES PATENT OFFICE.

CHARLES F. SCHRINER, OF CLEVELAND, OHIO.

BUSHING FOR METAL RECEPTACLES.

Application filed October 28, 1925. Serial No. 65,361.

This invention relates to bushings for metallic receptacles, and the main object of the invention is to provide a bushing of simple, inexpensive and practical construction, which may be quickly attached to a metal barrel or other receptacle in such manner that the bushing will be held against rotation when screwing a bung into or out of the bushing.

10 Another object of the invention is to provide a bushing of said character with provision for preventing leakage between the wall of the receptacle and the bushing.

15 For a full understanding of the invention reference will be had to the accompanying drawings illustrating same, and the novel features thereof will be particularly pointed out in the appended claims.

20 In the different views of the drawing, similar characters of reference are used to designate corresponding parts.

25 Figure 1 is a sectional elevation, taken on line 1—1 of Fig. 2 of a bushing applied to the end of a metallic receptacle in accordance with my invention,

Fig. 2 is a plan view of Fig. 1,

30 Fig. 3 is a sectional elevation of a bushing constructed in accordance with my invention, before the bushing is applied to the end of the metallic receptacle, and

35 Fig. 4 is a sectional elevation of the end of a metallic receptacle constructed in accordance with my invention for the application of the bushing.

40 Referring to the drawings, 1 represents the end of a sheet metal barrel or other receptacle, which is provided with an opening 2 formed by pressing therefrom an inward annular flange 3. A plurality of outwardly extending projections or lugs 4 are stamped from the end of the barrel, and the inner rounding edge 5 of said lugs are substantially at a right angle to the end of the barrel and the outer or upper sides 6 of said lugs are preferably inclined. The lugs 4 are arranged on the arc of a circle a sufficient distance from the inner edge of the opening 2 to leave a seat 7 for a sealing gasket 8. A bushing 9 of cylindrical formation and having an outer diameter corresponding to the inner diameter of an annular flange 3 for fitting therein is provided with a flange 10 and threaded internally at 11 for a bung. The outer edge of the flange 10 of the bush-

ing is notched or recessed at 12 for receiving the lugs 4 to hold the bushing against rotation. The other end of the bushing 9 is cut at 13 so as to leave a tapering portion for bending over the edge of the annular flange 3 as shown at 14. When the bushing 9 is assembled in the opening 2 of the end of the barrel, said bushing is securely held in position against rotation when screwing a bung into or out of the bushing, and the gasket 8 prevents leakage between the end of the barrel and the flange of the bushing.

45 From the drawings and description, it is obvious that a bushing for metallic receptacles thus constructed is simple and inexpensive to manufacture and assemble, will be securely held in position against rotation, and there will be no leakage between the wall of the receptacle and the bushing.

50 Having fully described my invention what I claim is:

1. The combination with the wall of a metallic receptacle of a bushing, the wall having an opening formed therein, a flange forming a seat surrounding the opening, lugs extending from the wall beyond said seat, the bushing having an annular flange at one end adapted to engage said seat, the flange of the bushing having notches cut in its edge for receiving and being engaged by said lugs, and the other end of the bushing being bent over the inner end of said annular flange of the bushing for clamping the bushing in position, substantially as described.

2. The combination with the wall of a metallic receptacle of a bushing, the wall having an opening formed therein, an annular flange forming a seat surrounding said opening, lugs formed integrally in said wall and extending beyond said seat, the bushing having a circular flange at its outer end, the circular flange of the bushing having notches cut in its outer edge adapted to fit over and be engaged by said lugs, a gasket arranged within said lugs and between said seat of said wall and said flange of said bushing, and the other end of the bushing being bent over the inner end of said annular flange for clamping the bushing into position, substantially as described.

100 In testimony whereof I affix my signature.

CHARLES F. SCHRINER.
